US0D1113778S

(12) **United States Design Patent** (10) **Patent No.:** **US D1,113,778 S**
(45) **Date of Patent:** **** Feb. 17, 2026**

(54) **DISPLAY SCREEN**

(71) Applicants: **GUANGZHOU SHIYUAN ELECTRONIC TECHNOLOGY COMPANY LIMITED**, Guangzhou (CN); **GUANGZHOU SHIRUI ELECTRONICS CO., LTD.**, Guangzhou (CN)

(72) Inventor: **Fengwen Liu**, Guangzhou (CN)

(73) Assignees: **GUANGZHOU SHIYUAN ELECTRONIC TECHNOLOGY COMPANY LIMITED**, Guangzhou (CN); **GUANGZHOU SHIRUI ELECTRONICS CO., LTD.**, Guangzhou (CN)

(**) Term: **15 Years**

(21) Appl. No.: **29/860,243**

(22) Filed: **Nov. 17, 2022**

(30) **Foreign Application Priority Data**

Jun. 10, 2022 (CN) 202230353692.3

(51) LOC (15) Cl. **14-03**

(52) U.S. Cl.

USPC **D14/126**; D14/127

(58) **Field of Classification Search**

USPC D14/126, 371, 374, 496, 239, 159, 129, D14/432, 483, 133, 203.7, 315, 125, 127

CPC G06F 3/04883; G06F 3/162; G06F 3/167; G06F 1/1605; G06F 1/1613; G06F 1/1601; G06F 1/1694
